FIG. 6.

INVENTOR
CHRISTIAN M. JACOBSEN
BY *Thomas J. Ryan*
ATTORNEY.

UNITED STATES PATENT OFFICE

CHRISTIAN M. JACOBSEN, OF NEWCASTLE, INDIANA

ADJUSTABLE HEADREST

Application filed October 22, 1931. Serial No. 570,410.

This invention relates to adjustable head rest devices, more particularly to devices of this character employed for supporting the heads of corpses while upon the cooling board and prior to the disposal thereof in the casket, and has for one of its objects to provide a simply constructed device which may be adjusted to control the height and also adapted to be set at any desired angle and locked in its adjusted position.

With these and other objects in view, the invention consists substantially in the construction herein described and claimed, and as illustrated in the accompanying drawings in which:

Figure 1 is a side elevation, partly in section, with the head rest elevated.

Figure 2 is a plan view of Fig. 1.

Figure 3 is an end elevation, partly in section, of Fig. 1.

Figure 4 is a side elevation with the parts in collapsed position.

Figure 5 is a view similar to Fig. 1, with the head rest in inclined position.

Figure 6 is a plan view of the base portion.

Figure 7 is an enlarged detail of the locking mechanism.

Figure 8 is a section on the line 8—8 of Fig. 7.

The improved device includes a base portion 10 having an elevated rim 11 and a plurality of spaced perforated ears 12 and spaced tooth bars 13, the latter each including a spaced guide member 14 as shown in Figs. 1, 2 and 3. The head rest portion includes a lower base portion 15 and an upper upholstered portion 16. Pivoted at one end at 17 to the under face of the member 15 are spaced bars 18, the latter in turn pivoted at their other ends respectively between the ears 12, as at 19. Pivoted at 20 to the under face of the member 15 at the end thereof opposite to the pivots 17, is another bar 21 which extends between the guard members 14 and also between the toothed bars 13, and is provided with a transverse pin 22 extending laterally to engage the teeth of the members 13. The pin 22 also extends beneath the guard members 14, and whereby the bar 21

is thereby prevented from upward displacement when the adjustments are made.

Pivoted at 23 to the under face of the head rest base 15 and between the side edges thereof is a tubular member 24, and slidably in the tubular member is a rod 25, the rod being pivoted at 26 to a cleat attached to the base 10 as shown. The member 25 is also tubular and provided with a plurality of spaced sockets 27, and pivoted at 28 to the lower end of the member 24 is a latch device 29, the upper end 30 of the latch being adapted to be projected through an aperture 31 in the member 24 and into one of the sockets 27, as shown in Fig. 8. A push rod 32 is attached at 33 to the outer end of the latch 29, and is carried upward and outward through the end of the head rest base 15 and terminates in a knob 34. The pivot 28 of the latch 29 operates in inclined slots 35, one of which is shown in Fig. 8, this providing a certain degree of play to the pivot 28 and obviating the necessity of using a spring to hold the latch in position. Thus when it is desired to raise or lower the head rest it is only necessary to push the knob 34 toward the head rest when the rod 32 will force the latch 29 downwardly and outwardly to the limit of the slots 35 which movement will withdraw the "toe" 30 of the latch from the socket 27 with which it is engaged, and release the head rest which may be raised, lowered or set at an angle as illustrated in Fig. 5, by manually adjusting the pin 22 in the teeth 14, as will be obvious. When the desired adjustment is completed, a slight pull upon the knob 34 will throw the point 30 of the latch into engagement with the nearest socket 27, and lock the head rest in its new position.

The device is simple in construction and can be readily adjusted to any desired height or angle, and without removing any of the parts.

Having now described my invention, that which I claim to be new and desire to secure by Letters Patent, is:

1. A device of the kind described, comprising a base, a head rest, rack teeth on the base, support means having pivotal connec-

tion at its one end with the base, and at its other end with the end portion of the head rest, support means having pivotal connection with the other end portion of the head rest and its lower end being engaged with said rack teeth, a telescopic member between the base and one end of the head rest, means operable to unite the sections of said telescopic member against movement one on the other when the head rest is in adjusted position, and operable to disunite said sections to permit them to move, one on the other, when the position of the head rest is to be adjusted.

15 2. A device of the kind described, comprising a base, a head rest, rack teeth on the base, opposed support bars each having pivotal connection at its one end with the base, and at its other end with the underside 20 of an end portion of the head rest, an intermediate support bar having pivotal connection with the underside of the other end of the head rest and its lower end being engaged with said rack teeth, a telescopic member 25 between the base and the head rest, means operable to unite the sections of said telescopic member against movement one on the other when the head rest is in adjusted position, and operable to disunite said sections 30 to permit them to move one on the other, when the position of the head rest is to be adjusted.

3. In a device of the kind described comprising a base, and a head rest, and means between the base and said head rest to support the latter at adjusted height and incline, means to hold the head rest in the position in which it is adjusted consisting of a telescopic member, the ends of whose sections are connected to the head rest and base, and means associated with said telescopic member, operable to unite the sections thereof against movement one on the other, and operable to disunite said sections to permit them to move, one on the other.

4. In a device of the kind described comprising a base and a head rest, and means between the base and said head rest to support the latter at adjusted height and incline, means to hold the head rest in the position in which it is adjusted consisting of a telescopic member, the ends of its sections being adapted to be connected to the head rest and to said base, one of said sections having spaced sockets in longitudinal alignment, and a latch device on the other of said sections operable to position engaged with, and operable to position disengaged from, said sockets.

In testimony whereof I affix my signature.

CHRISTIAN M. JACOBSEN.
